US00D971724S

(12) **United States Design Patent** (10) Patent No.: **US D971,724 S**
Stevenson et al. (45) Date of Patent: ** Dec. 6, 2022

(54) **CONTAINER WITH CUP CONNECTOR**

(71) Applicant: **F.D.S. Manufacturing Company**,
Pomona, CA (US)
(72) Inventors: **Kevin Tyrel Stevenson**, Upland, CA
(US); **Michael Cecil Francis Newman**,
Ontario, CA (US); **Robert Symons**,
Santa Ana, CA (US); **Steve Kwon**, San
Diego, CA (US)

(73) Assignee: **F.D.S. Manufacturing Company**,
Pomona, CA (US)

(**) Term: **15 Years**

(21) Appl. No.: **29/713,551**

(22) Filed: **Nov. 16, 2019**

(51) LOC (13) Cl. **09-03**

(52) U.S. Cl.

(57) **CLAIM**

The ornamental design for a container with cup connector, substantially as shown and described.

DESCRIPTION

FIG. 1 is a top perspective view of a cup connector, showing our new design, showing the cup connector independent from the container, to show aspects of the design not visible when combined;

FIG. 2 is another top perspective view thereof;

FIG. 3 is a top view thereof;

FIG. 4 is a bottom view thereof;

FIG. 5 is a front view thereof;

FIG. 6 is a rear view thereof;

FIG. 7 is left side view thereof;

FIG. 8 is right side view thereof;

FIG. 9 is a top perspective view of a container with cup connector;

FIG. 10 is a right-side view thereof; and,

FIG. 11 is an exploded perspective view thereof.

1 Claim, 11 Drawing Sheets
